(57) **CLAIM**

The ornamental design for an inline fluid filter, as shown and described.

DESCRIPTION

FIG. 1 is a front perspective view of an embodiment of an inline fluid filter.

FIG. 2 is a rear perspective view of the embodiment of FIG. 1.

FIG. 3 is a bottom view of the embodiment of FIG. 1.

FIG. 4 is a top view of the embodiment of FIG. 1.

FIG. 5 is a side view of the embodiment of FIG. 1.

FIG. 6 is a front view of the embodiment of FIG. 1; and, FIG. 7 is a rear view of the embodiment of FIG. 1.

The broken lines in the figures denote portions of the inline fluid filter that form no part of the claimed design. However, in embodiments other than those illustrated, lines that are currently illustrated as broken may be redrawn as solid lines, and lines that are currently illustrated as solid may be redrawn as broken lines. The scope of the present disclosure encompasses all lines illustrated, whether broken or solid. The inline fluid filter may be made of a variety of materials such as plastics and polymers, in some embodiments, and one or more components of the inline fluid filter may be made of transparent material, non-transparent material, partially transparent material, or any combinations thereof.
